UNITED STATES PATENT OFFICE.

ANDREW S. WITWER, OF JOLIET, ILLINOIS.

RECEPTACLE CLOSURE.

Application filed July 23, 1925. Serial No. 45,537.

To all whom it may concern:

Be it known that I, ANDREW S. WITWER, a citizen of the United States, residing at Joliet, in the county of Will and State of Illinois, have invented a new and useful Improvement in Receptacle Closures, of which the following is a specification.

My invention relates generally to receptacle closures, but more particularly to closures for paste tubes; and my object is to provide a novel, simple, and inexpensive form of such construction, and to provide for the issuing of the contents of the tube, when such contents are tooth paste, in a ribbon of a very desirable cross section.

Referring to the accompanying drawings:

Figure 1 is a plan view of the closure portion of a paste tube constructed in accordance with my invention, the rotatory cap portion thereof being removed, and the pin carried by the cap being shown in section. Figure 2 is a plan view of a slide forming a part of the closure. Figure 3 is a plan view 25 of the upper end of the tube with the slide removed. Figure 4 is a view like Fig. 1 showing the slide in open position. Figure 5 is a plan view of the closure construction showing the cap portion thereof by full lines in the position it occupies when the closure is open, and by dotted lines the position it occupies when the closure is in closing position. Figure 6 is an enlarged section taken at the line 6 on Fig. 1, and viewed in 35 the direction of the arrow, of the completed closure structure, showing it in closed position; and Figure 7 a similar view showing the closure in position to permit the contents of the receptacle to pass therethrough.

I have illustrated my invention in connection with a flexible, collapsible, tube, as for example for tooth paste, the receptacle-forming portion thereof being represented at 8 and provided at its upper end with an end piece 9 presenting an annular shoulder 10 surrounding the wall of the receptacle 8. The end piece 9 contains an aperture 11 of a shape presenting a substantially straight wall 12 shown as coincident with the center 50 of the end piece 9 and an arc-shaped wall extending from one end to the other of said straight wall. The outer face of the end piece 9 contains a recess 13 within the boundaries of which the opening 11 is located, this recess presenting the parallel guide 55 walls 14. Positioned in the recess 13 to be

slidable back and forth therein, is a slide 15 containing an aperture 16 of the same shape and size as the aperture 11, the parts being so arranged that when the slide 15 occupies the position shown in Fig. 1 the apertures 11 and 16 will be out of registration, as shown in Fig. 1, and when removed to the left in Fig. 4 to the position therein shown these apertures will be in registration. 65

The closure also comprises a cap portion 17 which extends across the end piece 9 and is rotatable thereon, the cap being prevented from separating from the end piece by providing an inwardly extending flange 18 70 which underlaps the shoulder 10 of the end piece. The cap 17 contains an aperture 19 of the same shape and size as the apertures 11 and 16 and so located as to register with the aperture 11 when the cap is rotated to a 75 certain position.

The slide 15 and cap 17 are provided with means whereby rotation of the cap in one direction shifts the slide to the left and rotation in the opposite direction shifts the slide to the right, a preferred embodiment of these means comprising a camming slot 20 in the upper surface of the slide 15 and a pin 21 depending from the cap 17 and extending into the slot 20. The various parts 80 of the construction are so proportioned and arranged, as shown, that when the cap 17 is rotated to a position in which the pin 21 extends into the slot as shown in Fig. 1, the slide 15 will be in a position in which its 85 aperture 16 will be out of registration with the aperture 11, in which position the outlet of the receptacle is closed; and when the cap 17 is rotated to a position in which the pin 21 is at the opposite end of the slot 90 95 20 the apertures 11, 16 and 19 will be in registration as shown in Fig. 7, the straight walls of these various apertures being in alignment in such position and affording an outlet for the receptacle of a shape corresponding generally to a segment of a circle. A closure constructed as shown and described, is not only of simple and economical construction, but operates very effectually as a movable closure, especially for use with pastes. 100 Furthermore, the provision of the outlet of the receptacle of the shape shown and described, is of advantage especially where the closure is used in connection with a tooth paste tube. 105

While I have illustrated and described a particular construction embodying my in-

vention, I do not wish to be understood as intending to limit it thereto, as the same may be variously modified and altered without departing from the spirit of my invention.

5. What I claim as new, and desire to secure by Letters Patent, is:

1. A closure device for a receptacle, comprising an end piece on the receptacle containing an aperture, a slide on said end piece 10 and containing an aperture positioned to register with the aperture in said end piece when said slide is in one position, an apertured rotatory member on said end piece, and means for imparting rectilinear movement to said slide by rotating 15 said member.

2. A closure device for a receptacle, comprising an end piece on the receptacle containing an aperture, a slide on said end piece and containing an aperture positioned to 20 register with the aperture in said end piece when said slide is in one position, an apertured rotatory member on said end piece and interlocked with the latter to prevent separation therefrom, and means for imparting 25 rectilinear movement to said slide by rotating said member.

3. A closure device for a receptacle, comprising an end piece on the receptacle containing an aperture of a shape presenting a 30 substantially straight wall and an arc-shaped wall extending from one end to the other of said straight wall, a slide on said end piece and containing an aperture positioned to register with the aperture in said end piece 35 when said slide is in one position, an apertured rotatory member on said end piece, and means for imparting rectilinear movement to said slide by rotating said member.

4. A closure device for a receptacle comprising an end piece on the receptacle con-

taining an aperture of a shape presenting a substantially straight wall and an arc-shaped wall extending from one end to the other of said straight wall, a slide on said end piece and containing a similarly shaped 45 aperture positioned to register with the aperture in said end piece when said slide is in one position, an apertured rotatory member on said end piece, and means for imparting rectilinear movement to said slide by rotating 50 said member.

5. A closure device for a receptacle, comprising an end piece on the receptacle containing an aperture and a slide-receiving guide-recess, a slide in said recess and containing an aperture positioned to register with the aperture in said end piece when said slide is in one position, an apertured 55 rotatory member on said end piece, and means for imparting rectilinear movement 60 to said slide by rotating said member.

6. A closure device for a receptacle, comprising an end piece on the receptacle containing an aperture, with its outer face recessed and forming a guide, a slide in said 65 recess and containing an aperture positioned to register with the aperture in said end piece when said slide is in one position, said slide containing a camming groove, a cap 70 rotatable on said end piece and interlocked with the latter to prevent separation therefrom, and a pin on said cap extending into said camming groove for imparting rectilinear movement to said slide when said cap is rotated, said cap containing an aperture 75 which registers with the aperture in said end piece when the aperture in said slide registers with the latter.

ANDREW S. WITWER.
